UNITED STATES PATENT OFFICE.

WERTHER ANDERS GUSTAF VON HEIDENSTAM, OF SKÖNVIK, SWEDEN.

APPARATUS FOR CHARRING WOOD REFUSE OR THE LIKE.

SPECIFICATION forming part of Letters Patent No. 777,415, dated December 13, 1904.

Application filed February 1, 1900. Serial No. 3,587. (No model.)

To all whom it may concern:

Be it known that I, WERTHER ANDERS GUSTAF VON HEIDENSTAM, a subject of the King of Sweden and Norway, and a resident of Skönvik, Sweden, have invented a new and useful Improvement in Apparatus for Charring Wood Refuse or the Like, of which the following is a specification, reference being had to the drawings accompanying and forming

10 a part hereof.

The invention relates to an apparatus for charring wood refuse, peat, or other materials under pressure either constant or variable. For the purpose in question the raw materials 15 have heretofore been formed or pressed into rods of suitable dimensions which have been subsequently heated in a corresponding retort under simultaneous compression as the charring process progresses. The compression is 20 effected by means of a plunger or like means which during the whole of the charring process or during the portion of same when contraction or shrinking occurs continually presses on the material with a constant pressure, so as to give the density required to the 25 charcoal. Owing to the fact, however, that with the method heretofore used the charring material is in contact with the walls of the retort, the said walls on account of the friction 30 developed absorb a portion of the pressure, and as a result the material farther away from the plunger is subjected to a considerably less pressure than that nearer the plunger. Charred rods are consequently obtained which 35 are not uniform in density, but of a density decreasing with the distance from the plunger. Another disadvantage resulting from the contact between the material and the retort is that the material is apt to stick in the 40 retort and have to be removed by extraordinary means.

These difficulties are overcome by the present invention, according to which the material is introduced in the retort in such a manner that it will not be in contact with the walls of the retort. To avoid bending or fracture of the material in the operation, the material is divided in sections and placed on special plates or disks loosely slipped onto one

or more rods or guides attached to the plunger and passing through the retort and apertures at the end of the latter. Charging and emptying the retort is quickly performed by the aid of said rod and a metal hood that covers the whole either while charring and cooling or only while cooling, so that the incandescent charcoal is not brought in contact with the atmosphere until after cooling.

In the accompanying drawings an apparatus for carrying out the process referred to is 60 shown in vertical sections.

Figure 1 shows the apparatus with the plunger in its lowest position. Fig. 2 shows the upper part of the same apparatus containing compressed charcoal, the cover being removed 65 and the charge ready to be lifted out to be cooled.

Referring to the drawings, 1 represents the retort in which the plunger moves. Said plunger is divided into two parts 2 and 3, 70 one of which, 2, is suspended on a flange 5 of the guide-rod 4. The compression is effected by means of hydraulic pressure acting on an attachment (not shown) of a shaft 12, supporting the plunger 2 3, or in other convenient 75 manner. The retort is covered at the top by a cover 8, which can be bolted in place by means of swing-bolts 6 and nuts 7 and is provided with a central aperture for the guide-rod. To prevent the charcoal from taking fire when 80 it is to be removed from the retort and while cooling, a hood 10, of metal plate or the like, is provided. Below the said hood is placed a cylinder 11 of the same diameter as the hood 10 for guiding the plunger. The said cylinder 11 may, however, be omitted, if desired. The cylinder 11 is provided with a bottom 13, to which is connected a tube 14 for letting 85 out the gases generated during the charring process and which is provided with a doorway 15 for cleaning purposes.

The method of charring may be carried out as follows: The material to be charred is made into briquets of suitable size and shape. A number of such briquets are placed upon 95 the part 2 of the plunger around the guide-rod 4 in such a manner that during the entire compression process the briquets will not

touch the walls of the retort. Said briquets are thereupon covered by a guide-plate 9, on which a fresh layer of briquets are placed, to be in their order covered by a similar plate, 5 &c. When enough has thus been arranged to about fill the retort, the hood is placed around the whole, which is thereupon lowered into the retort. The retort is now closed, as shown in Fig. 1, and the charge compressed as well 10 as heated in any suitable manner. When the charring is complete, the cover 8 is removed, and the charcoal mass is subsequently lifted out and allowed to cool in the hood. In place of performing the operation in the hood it is 15 evidently feasible to lift the charcoal up into the plate-hood after charring and transport said hood to the place where the cooling of the charcoal is to take place.

It is not necessary to make the material into 20 briquets before being placed between the guide-plates, since it is possible to place the same between said plates before any compression or shaping has taken place.

Having now described my invention, what I claim is—

1. The combination with a retort for charring wood refuse, peat or the like, of a plunger, and guide-rods provided with a bottom plate and a series of guide-plates, substantially as and for the purpose set forth.

2. The combination with a charring-retort for wood refuse, peat, or the like, of a plunger, guide-rods provided with a bottom plate and guide-plates adapted to divide the material into sections while being charred, and a 35 hood inclosing said guide-rods, guide-plates and charring material, substantially as and for the purposes set forth.

In testimony whereof I have signed my name to this specification in the presence of two sub- 40 scribing witnesses.

WERTHER ANDERS GUSTAF
VON HEIDENSTAM.
